LUBRICATOR

John L. Reilly, Claremont, N. H., assignor to Sullivan Machinery Company, a corporation of Massachusetts

Application January 9, 1934, Serial No. 705,909

3 Claims. (Cl. 121—13)

This invention relates to lubricators, and more particularly to lubricators particularly designed to use in pressure fluid actuated hammer tools, such as plug drills or the like.

An object of this invention is to provide an improved lubricator. Another object is to provide an improved lubricator for a pressure fluid motor whereby lubricant is supplied to the moving parts of the motor upon admission of pressure fluid to the motor. Another object is to provide an improved lubricator especially designed to use in hammer drilling tools, such as plug drills, or the like. A further object is to provide an improved lubricator for a pressure fluid motor whereby the supply of lubricant to the motor is controlled by the motor throttle valve. Yet another object is to provide in a tool of the above character an improved lubricator arranged and controlled in a novel manner whereby when motive fluid is supplied to the tool there is at the same time a flow of lubricant to the moving motor parts, the motive fluid and lubricant flow both being controlled by the motor throttle valve. These and other objects will, however, hereinafter more fully appear.

In the accompanying drawing there is shown, for purposes of illustration, one form which the invention may assume in practice.

In this drawing—

Fig. 1 is a longitudinal section through a hammer drilling tool equipped with the illustrative form of the improved lubricator.

Fig. 2 is a sectional view, taken substantially on line 2—2 of Fig. 1, with the parts in a different position.

Fig. 3 is a cross sectional view taken on line 3—3 of Fig. 1.

In this illustrative construction, the improved lubricator is shown embodied in a hand held, hammer drilling tool of the type commonly known as a plug drill, although it will be evident that the same may be embodied in tools of various other types. This drill herein comprises a cylinder 1 having a bore 2 containing a reciprocable hammer piston 3 adapted to deliver impact blows to the shank 4 of a working implement suitably mounted within the forward end of the tool. Secured to the rear end of the cylinder is a rear head plate 5, while secured to the member 5 is a valve chest member 6. The rear portion of the cylinder and the elements 5 and 6 are cylindrical in form, and arranged at the rear of the valve chest member 6 and abutting the rear end thereof, is a rear head block 7 having a sleeve-like portion 8 surrounding the rear end

of the cylinder and the elements 5 and 6. The elements 5, 6 and 7 are held in assembled relation with respect to the cylinder in any suitable manner. Formed in the valve chest member 6 is a valve chamber 9 having reciprocably mounted therein an automatic fluid distributing valve 10 which is adapted to control the flow of pressure fluid to and the exhaust from the opposite ends of the motor cylinder, thereby to effect actuation of the hammer piston. Pressure fluid is supplied to the valve chamber through a fluid supply connection 11 secured to the head block 7, the pressure fluid flowing from this supply connection through a transverse passage 12 and a communicating longitudinal passage 12^a, the latter in turn communicating with the valve chamber 9. The flow of pressure fluid to the passage 12^a is controlled by a throttle valve 13 arranged in and having a sliding fit with an axial bore 14 in the member 7, and having an intermediate groove 15 which connects, when the valve is in its forward position, the passage 12 with the passage 12^a. The means for controlling the throttle valve 13 comprises a sleeve-like portion 16 reciprocably mounted on the cylindrical portion of the head block 7 and having secured thereto a drill supporting member, herein a manual grasping handle 17. The rear end of the valve 13 abuts at 18 the inner wall of the sleeve portion 16, and is normally urged in such abutting position by means of pressure fluid supplied from the supply connection 11 through a passage 19 communicating with the valve bore 14 at the lower end of the valve, the pressure fluid acting on the lower face of the valve to urge the same into its uppermost position. The supply connection 11 projects through a slot 20 formed in the sleeve portion 16 of the handle, and engagement of the inner end of this slot with the connection 11 limits upward movement of the handle with respect to the motor cylinder. When the handle 17 is released by the operator, the pressure fluid acting on the valve 13 shoves the parts rearwardly into the position shown in Fig. 2, thereby cutting off communication between the passages 12 and 12^a and stopping the motor. When the operator shifts the handle 17 inwardly towards the drill cylinder, the throttle valve 13 is moved into the position shown in Fig. 1 to connect the passages 12 and 12^a, thereby to start the motor.

Now referring to the improved lubricator, it will be noted that formed in the rear head block 7 of the motor are parallel lubricant chambers or reservoirs 21, 21, herein two in number, al-

though more or less may be provided, as desired. These chambers or reservoirs are in the form of bores arranged at diametrically opposite sides of and parallel with the throttle valve bore 14, and are preferably of a length to extend substantially coextensive with the throttle valve bore, as shown in Fig. 2. These chambers communicate with the bore 14 of the throttle valve 13 through relatively restricted, forwardly inclined passageways 22, 22, these passageways, when the valve is in its released or closed position shown in Fig. 2, communicating with the groove 15. The chambers 21 are filled with lubricant through passages 23, 23 communicating with the lubricant chambers 21, 21 and having their outer ends closed by a detachable filler plug 24. The sleeve portion 16 of the handle is slotted at 25 to permit access to this filler plug. When the drill is turned onto its side and the filler plug 24 is removed, lubricant may be poured through the slot 25 and passages 23, 23 to the lubricant chambers, the filler plug thereafter being placed in position. When the parts are in the position shown in Fig. 2, lubricant flows from the chambers 21 through the passageways 22 to the groove 15, completely filling the space encircling this groove. When the hammer motor is started, the operator presses inwardly on the handle 17, thereby shifting the throttle valve 13 downwardly into its open position shown in Fig. 1, pressure fluid then flowing from the supply connection 11 through the passages 12 and 12^a to the chamber of the automatic distributing valve 10. Simultaneously, the lubricant retained in the groove 15 in the throttle valve is discharged into the passages 12 and 12^a and is entrained by the air flowing therethrough, and as a result, the lubricant is carried to the moving parts of the motor, namely the distributing valve or hammer piston, thereby to effectively lubricate the same. It will thus be seen that each time the hammer motor is started a small quantity of lubricant is carried to the motor parts. When the throttle valve is in its open position, the passages 22, 22 are closed so that no more lubricant may flow to the motor parts until the handle is again returned to the position shown in Fig. 2, and thereafter again shoved downwardly to the position shown in Fig. 1. When the lubricant in the reservoirs attains a level below the mouths of the passages 22, it has been found that lubricant still flows to the groove 15 and thence to the motor, due to the emulsification of the lubricant caused by pressure fluid leaking past the valve 13 to the reservoirs, and the vibration of the drill during operation. Also, in tools of the type disclosed, the same are frequently laid down on their sides during the drilling operation so that the lubricant may flow by gravity into the groove 15 even when the supply of lubricant in the reservoirs is low, thereby insuring frequent lubrication of the motor. It will also be evident that when the drill is in its inoperative position and is laid in any manner on the ground, no lubricant will flow from the chambers 21, 21 more than that necessary to fill the groove 15, and as a result waste of lubricant is eliminated. These and other uses and advantages of the improved lubricator will be clearly apparent to those skilled in the art.

While in this application there is shown one form which the invention may assume in practice, it will be understood that this form is shown for purposes of illustration, and that the invention may be modified and embodied in various

other forms without departing from its spirit or the scope of the appended claims.

What I claim as new and desire to secure by Letters Patent is:—

1. In a tool of the character described, a motor including a cylinder and a piston reciprocable therein, a rear head block for said cylinder, a tool supporting member slidably guided on said rear head block, said head block having parallel chambers, a plunger valve reciprocable in one of said chambers and engageable with said tool supporting member and actuated by the latter for controlling the supply of motive fluid to said cylinder, said valve having a recess for receiving lubricant and for conducting motive fluid and said head block having therein a passage controlled by said valve for supplying motive fluid to said reservoir for delivery to the motive fluid supply passage, said lubricant reservoir communicating through said passage means with said plunger valve recess when said valve is in one position and said plunger valve recess communicating with said motive fluid supply passage when said plunger valve is in another position.

2. In a tool of the character described, a motor including a cylinder and a piston reciprocable therein, a rear head block for said cylinder, a tool supporting member slidably guided on said rear head block, said head block having parallel chambers, a plunger valve reciprocable in one of said chambers and engageable with said tool supporting member and actuated by the latter for controlling a supply of motive fluid to said cylinder, said valve having a recess for receiving lubricant and for conducting motive fluid and said head block having a passage controlled by said valve for supplying motive fluid to said cylinder, said other chamber constituting a lubricant reservoir, and passage means controlled by said valve for supplying lubricant from said reservoir for delivery to the motive fluid supply passage, said lubricant reservoir communicating through said passage means with said plunger valve recess when said valve is in one position and said plunger valve recess communicating with said motive fluid supply passage when said plunger valve is in another position, said passage means including a lubricant discharge passage connecting the upper end of said reservoir with said plunger valve bore and with which said valve recess is communicable.

3. In a tool of the character described, a motor including a cylinder and a piston reciprocable therein, a rear head block for said cylinder having a cylindrical rearward portion, a tool supporting handle having a sleeve-like portion slidably guided on said cylindrical portion of said rear head block, said head block having an axial bore and parallel lubricant chambers arranged parallel to and substantially coextensive with said axial bore and communicating at their upper ends through lubricant discharge passages with said axial bore, a filler passage communicating with said parallel chambers whereby the latter may be filled with a lubricant, a plunger valve slidably guided in said axial bore and engaging said handle and actuated by the latter for controlling a supply of motive fluid to said cylinder, said valve also controlling said lubricant discharge passages, a passage controlled by said valve for supplying motive fluid to said cylinder.

said valve having a groove through which fluid flows to said motor cylinder when said lubricant discharge passages are closed by said valve, said groove communicating with said lubricant discharge passages when said motive fluid supply passage is closed by said valve, the groove in said

valve receiving lubricant from said discharge passages when said valve is in closed position and discharging said lubricant into said motive fluid supply passage when said valve is open.

JOHN L. REILLY.
